UNITED STATES PATENT OFFICE.

BERNARD H. MORRIS, OF NEWPORT NEWS, VIRGINIA.

METHOD OF MAKING VENTILATOR-TERMINALS.

1,243,437.

Specification of Letters Patent. Patented Oct. 16, 1917.

Application filed February 26, 1916. Serial No. 20,595.

To all whom it may concern:

Be it known that I, BERNARD H. MORRIS, a citizen of the United States, residing at Newport News, in the county of Warwick, State of Virginia, have invented a new and useful Method of Making Ventilator-Terminals, of which the following is a specification.

My present invention consists of a novel 10 method of making ventilator terminals, wherein tubular sections are formed and articulated together in a novel manner.

It further consists of a novel method of 15 making a curved tubular section for a ventilator terminal wherein circular sections, of semi-tubular form in cross-section, are first shaped from sheet-metal blanks and then welded together to form an annular tube and thereafter the tube is cut, preferably 20 on radial lines, in accordance with the length of the tubular section which is to be employed.

It further consists of a novel method of 25 forming curved sections for ventilator terminals, wherein the blanks of material are first spun on a die to form curvatures in the blank and thereafter the blank which has thus been treated is reversed and placed 30 on a die having a convex formation and spun to the shape of such die, thereby forming a circular section, of semi-tubular form in cross-section with a central connecting portion. The central portion of the blank 35 is then cut out. A second section is then made in a similar manner. The two sections are then welded or brazed together to 40 form an annular tube, which is thereafter cut, preferably on radial lines, and the juxtaposed ends of curved tubular sections are then deflected to form annular end flanges.

The flanges are then articulated by surrounding them with a band of any desired 45 contour in transverse section, and as shown, a U-shaped band is employed. The end section of a terminal, has connected therewith in any desired manner, preferably by soldering or welding, a tubular section, the outer portion of which flares outwardly and is 50 preferably bell-shaped, and this section terminates in an outwardly extending flange, which is spun to form an outer peripheral groove and a bead.

The end piece of the ventilator terminal 55 comprises a ring, having means to interlock with the peripheral groove of the end section and is provided with a foraminous

portion, such as for example wire mesh, which covers the opening in the end section.

The bottom or inner section may consist of a straight or curved section and, as illustrated, consists of a straight tubular section, having an annular groove near one end, thereby forming a flange which is articulated by means of a band with the end of a curved section. The straight tubular section is then provided with a damper, which is constructed and assembled in such a manner that it will interlock with the inner peripheral wall of a section to maintain the damper in its adjusted position.

Other novel features will hereinafter more clearly appear in the detailed description.

For the purpose of illustrating one manner of carrying out my novel method in practice, I have illustrated herein one type 75 of mechanism whereby a curved tubular section may be formed, but it is of course to be understood that such illustration is typical only of one manner of carrying out my invention, and that the invention may be 80 carried out by means of a variety of steps or mechanisms too numerous to illustrate or describe.

Figure 1 represents a sectional view of a die and a blank, illustrating the first step 85 of the operation.

Fig. 2 represents a sectional view of a die and a blank as the parts appear in the next step of the operation.

Fig. 3 represents a plan view showing the 90 parts as they appear after they have been welded together.

Fig. 4 represents a sectional view on line 4-4 of Fig. 3, in order to illustrate more clearly that the parts are welded or brazed 95 together.

Fig. 5 represents a sectional view on line 5-5 of Fig. 8 and on an enlarged scale showing more particularly the means to effect the locking of the damper.

Fig. 6 represents a plan view of a finished blank after the central portion thereof has been cut out and before it has been welded to another section.

Fig. 7 represents a side elevation of the 105 completed terminal.

Fig. 8 represents a sectional elevation of Fig. 7.

Similar numerals of reference indicate 110 corresponding parts in the figures.

Referring to the drawings:—

In practice, the terminal is usually made

of sheet metal of a non-oxidizable character, such as for example brass, and disks of the proper dimension are first cut out to form a sheet metal blank 1, (see Fig. 1).

5 2 designates a die which is used in the first step of the operation, said die having the outer flat face 3 at its central portion, which is provided with any desired type of fastening means, whereby the blank will 10 be held in assembled relation with respect to the die 2. The die 2 is provided with the rearwardly directed concave wall 4, which merges into the laterally extending straight wall 5. The die 2 is secured to the 15 rotating member of a lathe or other suitable machine in any desired manner, and in order to illustrate one manner of accomplishing this result, I have shown the die 2 as being internally threaded, as at 6, to engage the 20 threaded end of the lathe spindle.

Assuming now that the blank 1 has been fixed to the flat face 3 of the die 2, the lathe or other machine used to rotate the die is set into operation, and a tool of the usual 25 character used in spinning is applied to the outer face of the blank 1 so as to cause it to assume the shape of the die 2, so that it is spun into close relationship with the curved wall 4 and the straight wall 5. The 30 blank has now assumed the formation seen in dotted lines in Fig. 1, and as indicated at 7 in Figs. 1 and 2.

The die 2 is now removed from the lathe and a die 8 is then applied to the rotating 35 element of the machine, provision being made therefor, in the present instance, by internally threading the die 8 as at 9. The die 8 has its outer face provided with a central flat face 10 and the annular convex 40 face 11.

The blank 7 is now reversed so that the central portion thereof engages the flat face 10 and assumes the position seen in full lines in Fig. 2. The die 8 is now caused to 45 revolve and the usual tool used in spinning is brought into contact with the outer face of the blank and causes the outer portion of the blank 7 to be brought into close engagement with the outer convex face of the 50 die 8 and to assume the contour seen in dotted lines in Fig. 2, and as indicated at 12.

The central flat portion of the finished blank is then cut away at 13, and the blank has now assumed the shape seen in Fig. 3 55 having the flat edges 14 and 15, and forms a circular section of semi-tubular form in cross-section. Another blank is then taken and treated in a similar manner, and when two of the circular sections of semi-tubular 60 form in cross-section seen in Fig. 6 have been formed, the edges 14 and 15 are brought together and welded or brazed, as indicated at 16 in Fig. 4, so that an annular tube 17 is formed, as indicated at Fig. 3. This tube 65 is then transversely cut, preferably on ra-

dial lines, as indicated at 18, to form sector-shaped curved tubular sections of the desired lengths. The ends of the sector-shaped curved tubular sections are then laterally deflected to form end flanges 19 and juxtaposed flanges articulated together by means of a band 20. The flanges 19 are preferably deflected, so that they will make practically a line contact with the band and eliminate in a large measure the friction which would be present if they contacted with the band throughout their juxtaposed surface.

I preferably employ two sector-shaped curved tubular sections 21 and a straight tubular section 22, which latter consists of 80 a ring or collar which may be of the same or greater thickness than the thickness of a curved section and is provided at its outer end with an annular groove 23, thereby forming a flange 24 so that by means of a 85 band, such as 20, the flange 24 may be articulated with a flange 19 of a sector-shaped curved section. The straight tubular section 22 is provided with a damper 25 carried by trunnions 26, one of which is adapted to be manipulated in order to adjust the position of the damper. The damper is locked in its adjusted position by means of a semi-circular rod member 27, the ends of which are connected with the damper 25 95 and this semi-circular member 27 is provided with a desired number of grooves or notches 28 which interlock with an inwardly projecting lug or bar 29 on the inner periphery of the tubular section 22.

The outer end of the curved sections has united therewith in any desired manner, for example, by soldering, an outwardly flared tubular section 30 which forms an integral part thereof and which is provided with a 100 forwardly extending flange 31, in which a peripheral groove 32 is spun, and the free end of such section 30 is spun into a bead 33, it being understood that the part 30 of the section 21 has its inner end spun inwardly to form an offset flange 34, which can be welded or soldered to the curved section 21 so that the outer periphery of the sections form, when assembled, continuous curves irrespective of the manner in 105 which the sections have been relatively adjusted. The end piece is next formed, which comprises a ring 35 which is spun into a curved formation substantially angular in cross section, and provided with inwardly 110 extending lugs 36, which are sprung over the bead 33 and interlock with the walls of the groove 32 when the end piece is sprung into position.

The ring 35 carries a foraminous portion 125 37, formed in the present instance by a wire mesh, the outer periphery of which is soldered or otherwise connected to the inner periphery of the ring 35, which forms the end piece.

In accordance with my present invention, I preferably employ a plurality of curved pipe sections, which are articulated on a diagonal or radial line, as is indicated at 38, 5 so that by means of two curved tubular sections, the mouth or outer opening in the ventilator terminal may be presented in any desired direction, as will be apparent to those skilled in this art.

10 It is also within the scope of my invention to form the circular sections, of semi-tubular form in cross-section, one of which is shown in Fig. 6, by casting the same in a mold or by stamping, which can be readily accomplished at a minimum cost, and when manufactured in large quantities, the semi-tubular parts would be preferably formed by stamping or pressing them into shape.

The parts of a tubular section are then 20 united in the manner hereinbefore described to form an annular tube 17 (see Fig. 3), and the other further steps in the manufacture of the completed terminal are the same as those already described.

25 It will be seen that in accordance with my present invention, the joint formed by adjacent tubular sections is made by bringing a band into assembled relation with respect to the juxtaposed end flanges of sections, so 30 that each section is relatively movable with respect to the band. By such means, a double joint is formed, so that in case one of these joints becomes corroded or rusted and rendered immovable, the other joint can be 35 used and the requisite adjustment of the terminal effected.

In devices heretofore employed of this character, it has been customary to employ an ordinary stove pipe joint, which soon becomes corroded and is difficult of adjustment. The ventilator terminals are 40 specially adapted to be used in connection with the ventilating systems of ships, although, as is apparent, they may be used in connection with any desired type of ventilating or other system, in which the end of a conduit is to be presented at different positions in order to collect or distribute the air to a desired point of utilization.

50 The bottom or base section is spun or stamped into shape and the sections are then united together in any desired manner. The end section 30 and the ring 35 are preferably formed by spinning or stamping to a 55 semi-tubular shape and then uniting two of such members.

The notch receiving portion of the member 27 preferably has its outer periphery formed with a shorter radius in order to permit it to ride over the lug 29 which engages when the damper is in closed position with the walls of the recess formed by the member 27 and the damper. The annular tube formed by uniting sections such as shown in Fig. 6 provides, when transversely 60 cut, curved tubular sections of desired 65 lengths.

The sections are preferably buffed, plated and polished in any desired or conventional manner.

70 Having thus described my invention, what I claim as new and desire to secure by Letters Patent, is:—

1. The method of making tubular sections, 75 which consists in forming blanks into sections each of which has a central portion and a circular portion, of semi-tubular form in cross-section, surrounding the said central portion, cutting out the central portions of said sections, uniting the said sections 80 to form a tubular annulus, and cutting the annulus into tubular sections of desired lengths.

2. The method of making ventilator terminals, which consists in forming blanks 85 into sections each of which has a central portion and a circular portion, of semi-tubular form in cross-section, surrounding the said central portion, cutting out the central 90 portions of said sections, uniting the said sections to form a tubular annulus, cutting the annulus into tubular sections of desired lengths, and articulating the juxtaposed ends of sections.

3. The method of making ventilator terminals, which consists in spinning blanks 95 into semi-tubular grooved members, cutting out the central portions of said members, uniting said members to form a tubular annulus, cutting the annulus into tubular sections 100 of desired lengths, and articulating the juxtaposed ends of sections.

4. The method of making tubular sections which consists in forming two annular sections of semi-tubular form in cross-section, 105 connecting the opposed edges of said sections, and cutting the tubular annulus thereby provided into sector-shaped sections.

BERNARD H. MORRIS.
